UNITED STATES PATENT OFFICE

GEORGE L. GILBERT, OF LAKEWOOD, OHIO

DESIGN FOR A COMBINED RADIO AND PHONOGRAPH CABINET

Application filed September 6, 1930. Serial No. 36,884. Term of patent 14 years.

To all whom it may concern:

Be it known that I, GEORGE L. GILBERT, a citizen of the United States, residing at Lakewood, in the county of Cuyahoga and State of Ohio, have invented a new, original, and ornamental Design for a Combined Radio and Phonograph Cabinet, of which the following is a specification, reference being had to the accompanying drawings, forming part thereof.

In the drawings

Fig. 1 is a front perspective view of the combined radio and phonograph cabinet showing my new design,

Fig. 2 is a top plan view of the cabinet.

Fig. 3 shows a side elevational view of the same; and

Fig. 4 shows a front perspective view with three of the doors in open position for the purpose of showing the interior features of the ornamentation.

I claim:

The ornamental design for a combined radio and phonograph cabinet, as shown and described.

In testimony whereof I affix my signature.

GEORGE L. GILBERT.
